KNOB SPINDLE SECURING MEANS

Clifford P. Wicks, Stamford, Conn., assignor to
The Yale & Towne Manufacturing Company,
Stamford, Conn., a corporation of Connecticut

Application June 2, 1947, Serial No. 751,689

3 Claims. (Cl. 292—336.5)

1

This invention relates to a lock, and more particularly to means for securing a spindle in assembled relation to a lock.

It frequently becomes desirable to secure a spindle to a lock, and then to secure to the spindle a knob, with the parts so arranged that the knob and spindle cannot be moved away from assembled relation to the lock. In this way, the several parts are held in operating relationship. It is the object of my invention to contribute means whereby a spindle may be readily assembled to a lock without the utilization of special tools or removable fastening elements.

As a feature of the invention, I utilize a spindle that is readily assembled to a lock part, preferably the rollback, so as to rotate the rollback while simultaneously effecting a locking of the spindle against endwise axial removal from the rollback. It is a particular feature of this part of the invention that the assembly of the rollback and spindle requires no tools or movable fastening means.

As still a further feature of the invention, the spindle is formed of a plurality of longitudinally extending parts whereby it is adapted for rigid assembly to a knob, the spindle parts being secured to one another at one end for effecting assembly simultaneously to a rollback.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention.

Referring now to the drawings, Fig. 1 is a vertical section through a rollback, spindle and knob constructed in accordance with the teachings of my invention. Fig. 2 is a section taken along lines 2—2 of Fig. 1. Fig. 3 is a partial section in elevation taken along lines 3—3 of Fig. 1. Fig. 4 is an exploded view of the knob, spindle and rollback of my invention.

Referring now more particularly to the drawings, reference numeral 10 indicates a rollback of the type adapted for rotation by a spindle and equipped with a cam portion 11 for retracting a bolt or the like as those skilled in the art will understand. The rollback 10 is formed with a bore

2

0 having a square axial elevation adapted for coaction with a square spindle. This bore 0 is defined by upper and lower surfaces designated respectively by reference numerals 12 and 13 in Fig. 1, and by side surfaces 14 and 15. Each end of the rollback bore 0 is enlarged as shown at 16 and 17 in Fig. 1. Similarly the internal portion of the bore 0 is enlarged as best shown at 18 in Fig. 1.

10 Adapted for insertion into the bore 0 of the rollback 10 is what is known in the art as a triplex spindle S formed of three parts 19, 20 and 21. Preferably, the three parts 19, 20 and 21 are brazed together at one end as shown at 23 in Fig. 15 4, but are maintained separated at the other end, the extreme left end in Figs. 1 and 4. A suitable cross slot 25 is cut in the brazed end of the spindle and this slot is adapted for cooperation with a pin 26 mounted in a hole 27 of rollback 10 with 20 part of the pin obstructing bore 0 of the rollback.

A knob K is formed with a square opening 22 into which extends a threaded stud 24 of the type well known in the art. The left end of the spindle S is inserted into the opening 22 as shown in Fig. 25 1 and thereafter the threaded stud 24 is rotated to bring pressure against one of the three spindle parts, here the part 20. This pressure by stud 24 spreads the spindle parts against the surfaces of the opening 22 of the knob K and securely secures the knob to the spindle, all as those skilled in the art will appreciate.

When it is desired to assemble to a door a lock equipped with the rollback 10, the lock is first placed in the door in position to accept spindle S through the usual side openings. Spindle S is then moved into alignment with its dash and dotted line position of Fig. 1 and then downwardly to bring the slot 25 under the cross pin 26. It will be possible thereafter to move the 40 spindle S to its operating position shown in full lines in Fig. 1.

With the spindle in the full line position of Fig. 1, it is obvious that it is retained against axial movement relatively to the rollback 10. Thereafter, the knob K may be applied to the left end 45 of the spindle as already set forth. So long as the knob and spindle are in the particular relationship of Fig. 1 to the rollback, and this will be the relationship of the parts when they are assembled in a lock and door and there held by roses or the like, the spindle will be retained against removal from the lock and the knob will be held on the spindle.

It is now obvious that by the utilization of extremely simple means I make it possible to secure

my spindle to a rollback, while utilizing the preferred triplex spindle construction well known in the art. It is obvious further that my invention makes it unnecessary to use assembly tools or fastening means of any sort, as it is merely by a manipulation of the parts that the spindle is fastened to the rollback. It is obvious further that the spindle may be removed from the rollback at any time by merely moving it angularly back to its position in dash and dotted lines shown in Fig. 1 and then outwardly.

I now claim:

1. In a combination of the class described, a rotating rollback cam having an axial square bore, a square spindle adapted to fit in said bore so that rotation of said spindle effects rotation of said rollback, said bore being enlarged at one side of the rollback and above the central longitudinal axis of said bore, said bore being also enlarged centrally of said rollback and below said axis for the insertion of the spindle into said bore in a direction at an angle to the axis of rotation of said rollback cam, and surfaces formed on said spindle and rollback cam adapted to interlock as said spindle enters said axial bore of said rollback cam at said enlarged side and moves into axial alignment therewith, whereby said spindle is locked against axial movement out of said bore.

2. In a combination of the class described, a rotating rollback cam having an axial square bore, a square spindle adapted to fit in said bore so that rotation of said spindle effects rotation of said rollback, said bore being enlarged at one side of the rollback and above the central longitudinal axis of said bore, said bore being also enlarged centrally of said rollback and below said axis for the insertion of the spindle into said bore in a direction at an angle to the axis of rotation of said rollback cam, a surface on said rollback

obstructing said axial bore, and a surface formed on said spindle adapted to interlock with said rollback surface as said spindle enters said axial bore of said rollback at said enlarged side and moves into axial alignment therewith, whereby said spindle is locked thereafter against axial movement out of said rollback bore.

3. In a combination of the class described, a rotating rollback cam having an axial square bore, a square spindle adapted to fit in said bore so that rotation of said spindle effects rotation of said rollback, said bore being enlarged at one side of the rollback and at one side of the central longitudinal axis of said bore, said bore being also enlarged centrally of said rollback and at the other side of said axis for the insertion of the spindle into said bore in a direction at an angle to the axis of rotation of said rollback cam, a surface on said rollback obstructing said axial bore, and a surface formed on said spindle adapted to interlock with said rollback surface as said spindle enters said axial bore of said rollback at said enlarged side and moves into axial alignment therewith, whereby said spindle is locked thereafter against axial movement out of said rollback bore.

CLIFFORD P. WICKS.
